AUXILIARY TUB ATTACHMENT FOR WASHING MACHINES

Filed July 12, 1945

Fig. 1

FIG. 2.

UNITED STATES PATENT OFFICE

2,439,469

AUXILIARY TUB ATTACHMENT FOR
WASHING MACHINES

Harry F. Husted, Shavertown, Pa.

Application July 12, 1945, Serial No. 604,619

5 Claims. (Cl. 68—4)

1

This invention relates to washing machines.

An object of this invention is to provide an attachment for a washing machine whereby small articles can be washed in the regular size machines without using the normal amount of water and soap, the attachment being mounted within the tub and forming a reduced size inner removable tub which is positioned about the regular agitator and is held in watertight position relative to the main tub bottom by means of suction cups.

Another object of this invention is to provide an attachment of this kind which can be applied to or removed from the tub without changing any of the present parts of the tub or the machine.

A further object of this invention is to provide an attachment of this kind which includes a cylindrical auxiliary tub of a diameter substantially smaller than and of a height less than the main tub for engagement about the agitator, a plurality of suction elements fixed to the auxiliary tub for holding the latter about the agitator and a sealing ring on the lower end of the auxiliary tub for contact with the bottom of the main tub whereby the cleaning fluid will be retained in the auxiliary tub.

To the foregoing objects, and others which may hereinafter more fully appear, the invention consists of the novel construction, combination and arrangement of parts as will be more specifically referred to and illustrated in the accompanying drawings but it is to be understood that changes, variations and modifications may be resorted to which fall within the scope of the invention, as claimed.

Referring to the drawings:

Figure 1 is a vertical section of a washing machine having an attachment constructed according to an embodiment of this invention.

Figure 2 is a top plan view of the attachment.

Figure 3 is a fragmentary sectional view taken on the line 3—3 of Figure 2.

In the drawings the numeral 10 designates generally a main tub of a washing machine which is formed of an upright or cylindrical wall 11 and a bottom wall 12. An agitator structure 13 is rotatably mounted within the main tub 10, being centrally disposed and adapted to be oscillated by conventional means (not shown).

In order to provide a means whereby a small number of small articles may be washed within the tub 10, without filling this tub to the usual height, or discharge unnecessarily soap or soap powder into the water, I have provided an auxiliary structure, generally designated as 14, which

2

is in the form of an attachment for removable engagement within the main tub 10. The auxiliary tub 14 comprises a cylindrical wall 15 having spaced reinforcing ribs or beads 16 and 17, and an inturned upper edge 18.

The cylindrical wall 15 has secured to the lower end thereof, a sealing member, generally designated as 19. This sealing member 19 comprises a resilient tubular member 20 which has extending therefrom a channel member 22 within which the lower edge of the cylindrical wall 15 is adapted to snugly engage. The sealing member 20 and the channel member 22 are formed as a continuous ring, and the inherent resiliency of the walls of the channel 22 will provide for the maintaining of the sealing member on the lower end of the side wall 15. The tubular member 20 is adapted to engage the upper surface of the bottom wall 12, as shown in Figure 1, and to be disposed in sealing position by means of a plurality of resilient suction cups 23.

Right angular cup supporting arms 24 have one side 25 thereof secured to the outer side of the cylindrical wall 15, and the other side 26 thereof extending radially outwardly.

A threaded bolt or stem 27, which is carried by the sealing cup 22, is adapted to engage through an opening 28 formed in the outwardly extending side 26, and removable nut member 29 is threaded on the bolt 27 so as to clamp the cup member 23 on the side or arm 26.

As shown in Figure 3, the cup members 23 normally have the lower edges 30 thereof disposed slightly above the lower edge or surface 31 of the sealing member 20. In this manner the sealing member 20 will be assured of being distorted before the cup members 23 are in clamping engagement with the bottom wall 12.

In the use of this attachment the auxiliary tub 14 has a diameter substantially less than the diameter of the main tub 10, and may also have a height substantially less than the height of the lower tub 10. The diameter of the auxiliary tub 14 is slightly greater than the outer diameter of the agitator 13 so that the latter may freely oscillate within the auxiliary tub.

The auxiliary tub is pressed downwardly onto the bottom wall 12 and the suction members 23, disposed in clamping engagement with the bottom wall so as to maintain the sealing member 20 distorted and in sealing engagement with the bottom wall. The water or liquid which is used for cleaning the articles disposed within the auxiliary tub may then be placed within this tub

to the desired height, and the agitator 13 is operated in the normal manner.

This device will provide a removable attachment by means of which a large main tub of a washing machine may be used for washing a small number of articles which may be of small size and which, under normal conditions, cannot be washed alone in the main tub in an economical manner.

I claim:

1. In combination with a main wash tub of a washing machine above whose bottom projects an agitator centrally, a tubular shell placed upon the bottom of the main tub so as to surround the agitator and provide between the tubular shell and the shell of the main tub an annular space, whereby the bottom of the main tub forms a bottom for the tubular shell, an annular hollow compressible bead carried by the lower edge of the tubular shell resting upon the bottom of the main tub, and means frictionally engaging the bottom of said main tub in said annular channel securing a tight hold upon said bottom and engaging said tubular shell to compress the bead in fluid tight sealing relation upon the bottom of the main tub.

2. In combination with the main wash tub of a washing machine above whose bottom projects a rotatable agitator, a tubular shell seated upon the bottom of the main tub so as to make the bottom of the main tub the bottom of the tubular shell and so as to completely surround the agitator to provide between the tubular shell and main tub an annular space, a plurality of suction cups rigidly carried by the lowermost part of the tubular shell and stationed in said annular space, for engaging the bottom of the main tub for the purpose of preventing lateral or vertical shifting of the tubular shell in said main tub, and sealing means covering the lowermost edge of the tubular shell and engaging the bottom of the main tub, caused by said engagement of suction cups with the bottom of the main tub to press the tubular shell into fluid sealing relationship with said bottom of the main tub.

3. In a washing machine, a main tub having a bottom, a washing machine agitator operatively positioned centrally in the bottom of the main tub, an auxiliary removable tubular shell open at its top and bottom positioned upon the bottom of the main tub so as to directly enclose the agitator and have the walls thereof spaced from those of the main tub so the agitator works in

the auxiliary shell alone, while the bottom of the main tub forms the bottom of this auxiliary shell, an annular compressible bead member attached to the lower edge of the auxiliary shell, and means in said main tub outside of the auxiliary shell frictionally and removably engaging the bottom of the main tub and engaging the auxiliary shell for pressing the bead member upon the bottom of the main tub to provide a constantly held fluid

10 tight seal between said tub and shell.

4. As a new article of manufacture a tubular shell open at its bottom, an annular compressible bead fitted against the lower edge of the shell so as to cover the same resiliently, and a plurality 15 of radially disposed supporting members for the shell, each of said members consisting of a suction cup and an arm secured to the side of the shell so as to dispose the suction cup parallel to the axis of the shell and so that the lowermost 20 part of the extended bead normally extends below the suction cups so as to slightly elevate the shell from the surface to be engaged by said suction cups.

5. As a new article of manufacture an open 25 ended tubular shell, an annularly disposed compressible sealing member on one end of said shell, peripherally disposed shell supporting members carried by said shell, said latter members including a suction cup for engagement with the surface 30 to which said shell is to be attached, said suction cups and said sealing member being so related that said sealing member will be compressed upon the engagement of said suction cups with the surface on which the shell is attached.
